UNITED STATES PATENT OFFICE

2,517,119

COMBINED ROAD SIGNAL AND UTILITY BOX

Joseph Edouard Le Duc, Mount Royal, Quebec, Canada, assignor of twenty-five per cent to Leonard Lemieux and twenty-five per cent to Rodolphe Cote, both of Montreal, Quebec, Canada

Application April 29, 1947, Serial No. 744,761

1 Claim. (Cl. 177—329)

1 This invention relates to a combined road signal and utility box.

The device of the present invention is primarily a tool kit or tool-containing box, but it also includes a means, conveniently carried on the underside of the tool kit closure or lid, for projecting light rays through a window, the lid being adapted to be releasably locked in an upstanding position so that such lid will serve as the signalling instrumentality.

The objects of the invention, generally, are to provide a new and very useful device which includes a tool kit and a signalling device, the device being put to use when the tool kit is laid upon the road or adjacent to the road, preparatory to effecting repairs to a stopped or stalled car on the highway.

A specific object of the invention is to provide in such device collapsible and folding tool-receiving compartments which are compactly held within the device or box but may be swung out of the device to hang along a wall of the box, after the closure has been raised into upstanding position.

Another specific object of the invention is to so form the lid and lid-receiving opening in the top wall as to enable the lid to be removably held securely in an upstanding position.

Another specific object of the invention is to provide a means on the underside of the closure removably holding a suitable lighting means, such as a standard flashlight.

In the drawings, wherein like numerals of reference indicate corresponding parts in the various figures:

Figure 1 is a perspective view of a device made according to the invention, in closed position;

Figure 2 is a perspective view of the device, in opened or operative position;

Figure 3 is a transverse section on line 3—3 in Figure 1;

Figure 4 is a side elevation of the device or box in set up position, shown partly in section;

Figure 5 is a front elevation of the box cover panel in set up position;

Figure 6 is a perspective view of the panel when used as a warning signal suspended from the end of, say, a pipe projecting from the back of a vehicle;

Figure 7 is a fragmentary, vertical section of the panel, with flashlight attached for night illumination;

Figure 8 shows the modified flashlight supporting arrangement; and,

2 Figure 9 is a transverse section on line 9—9 in Figure 5.

Referring now by numerals to the drawings, **10** shows an elongated box, of which **11** are the side vertical walls and **12** the top wall. The top wall is formed with an elongated opening **13**, preferably substantially lozenge in shape. The opening is provided with laterally extending portions **14** at the smaller end of the opening, these portions in effect forming notches through the top wall **12**.

15 **15** is the lid or closure for the opening, the lid conveniently resting upon shoulders **16** formed by recessing the end walls **17**, as best shown in Figure 4. The lid is provided at one end with suitable leather straps **18** adapted to extend beyond the adjacent end of the box to be bent down and removably fastened to suitable buttons **19** (see Figures 1 and 4).

The box is adapted to hold a number of tools and other objects. The tools, which usually are wrenches of several types, pliers, screw drivers, bolts and the like, are conveniently stored in flexible or collapsible tool-receiving containers or pouches **20** formed to be laid one upon the other, when within the box (as best shown in Figure 3). The pouch is formed from a rectangular piece of suitable fabric—say strong duck—which is folded upon itself and secured along the outer edges of the two folds and adjacent the upper edge of the side wall, also as best seen in Figure 3. The pouches can thus be lifted out of the box, that is, swung on their outer edges, to be hung in front of the side vertical walls. The pouches are so sized that they will extend substantially across the width of the box, so that two such pouches will have appreciable capacity while allowing space thereunder for storing other tools such as a jack **22**, a handle **23** therefor, tire tools **24** and others.

In order to facilitate the task of moving the tool box over the road, as from the trunk compartment to a front wheel, for instance, a roller **26** is journaled at the rear end of the box.

45 Preferably, a suitable reflector **27** is suitably secured to the outer face of the rear wall.

The lid **15** carries on its upper face a plate **29** of suitable material on which letters spelling "Danger" are applied as by luminous paint or the like, the letters acting as so many reflectors, or vice versa.

Adjacent the top of the lid **15** is a window or opening **30** in register with an opening **31** made through the plate **29**.

55 The means used for projecting light rays

through the window 30 may be as shown in Figures 7 and 9. Thus, a standard flashlight 33 is supported in upstanding position upon a bracket 34 which includes a horizontal member 35 formed with an opening in register with the longitudinal axis of the flashlight, and a vertical member 36 formed with laterally extending portions adapted to be slidably received in a suitable guide member 37 secured to the underside of the lid. The flashlight is held in position as by a more or less cone-shaped sleeve 39 engaging the bell-shaped end of the flashlight and formed with a marginal flange 40 which is received into a pair of grooved members or guides 41 secured to the horizontal member 35 of the bracket 34. Mounted at one end to the bracket 37 is a mirror 42. Preferably, the mirror is pivotally supported to the bracket as at 43.

If preferred, the flashlight may be of the standard elbow type. Such flashlight, 33a, may be removably secured to the lid as by a substantially cone-shaped sleeve 44 formed with a marginal flange 45 adapted to be received into grooved members 46 secured to the underside of the lid, as best seen in Figure 8.

Preferably, as shown in Figures 7 and 9, a coloured (red) glass or lens 48 is positioned behind the window 30.

Obviously, the underside of the lid may be utilized to hold objects useful when travelling, as for instance, first-aid kits 49, flares 50 and a flag 51.

What I claim is:

In a road signal unit, a box, a lid adapted to be held in upstanding position above the box, said lid having an aperture therethrough, a coloured lens closing said aperture, a bracket extending at right angles to the plane of the lid, said bracket having an opening therethrough in alignment with the aperture of the lid, and having guides on either side of said opening, a flashlight formed with a bell-shaped end, and a substantially cone-shaped sleeve adapted to engage said bell-shaped end of the flashlight and formed with a marginal flange removably and slidably received into said grooves and holding said flashlight in upstanding position, the bell-shaped end of the latter being in alignment with the coloured lens.

JOSEPH EDOUARD LE DUC.
